CLAIM

We claim the ornamental design for a locking pliers jaw, as shown and described.

DESCRIPTION

FIG. 1 is a right side view of our new design for a locking pliers jaw, the left side view being identical;

FIG. 2 is a front view showing our new design shown in FIG. 1;

FIG. 3 is a back view showing our new design shown in FIG. 1;

FIG. 4 is a top view showing our new design shown in FIG. 1; FIG. 5 is a bottom view showing our new design shown in FIG. 1; and,

FIG. 6 is a perspective view showing our new design shown in FIG. 1.

The portions shown in broken lines are not part of the claimed design but show the environment in which the design is associated.
